UNITED STATES PATENT OFFICE

WILLIAM E. FRANK, OF ST. LOUIS, MISSOURI, ASSIGNOR TO FOSTER BROTHERS MANUFACTURING COMPANY, OF ST. LOUIS, MISSOURI, A CORPORATION OF MISSOURI

FOLDING COUCH OR DAVENPORT

Application filed September 22, 1924. Serial No. 739,101.

This invention relates to folding couches, davenports and day beds of the type in which the mattress supporting means is composed of two relatively narrow sections arranged in 5 superimposed relation when the couch is closed and combined with an operating mechanism in such a manner that the top section will move forwardly without reversing into a position in front of the bottom section, and 10 the bottom section will move upwardly into horizontal alignment with the top section during the operation of opening the couch, thus forming a supporting means that is wide and long enough to sustain a conventional full 15 width bed mattress.

The main object of my present invention is to provide a folding couch or davenport of the particular type mentioned in which the bottom section of the mattress supporting 20 means is so constructed and arranged that the front edge of same will tilt downwardly sufficiently, during the operation of opening and closing the couch, to insure the rear edge of the top section of the mattress supporting 25 means clearing the folded mattress that normally rests upon said bottom section when the couch is closed, thereby facilitating the operation of opening and closing the couch and making it practicable to equip the couch with 30 a relatively thick mattress or pad.

Another object is to provide a folding couch or davenport of the type referred to that is inexpensive to construct; that is strong and rugged enough to successfully withstand 35 rough usage and which is of such design that it can be opened and closed easily by exerting a slight pull or push on the top section of the mattress supporting means.

40 Figure 1 of the drawings is a perspective view, partly broken away, of a folding couch or davenport constructed in accordance with my invention.

Figure 2 is a transverse sectional view of the 45 couch, showing it open.

Figure 3 is a transverse sectional view, showing the couch closed.

50 Figure 4 is a top plan view, showing the construction and arrangement of some of the elements of the operating mechanism com-

bined with the two sections of the mattress supporting means; and

Figure 5 is an enlarged transverse sectional view, illustrating how the front edge of the bottom section of the mattress supporting 55 means tilts downwardly during the operation of opening and closing the couch.

Referring to the drawings which illustrate the preferred form of my invention, A and B designate the top and bottom sections, respectively, of the mattress supporting means, each of which sections consists of a rigid frame of substantially oblong shape in general outline equipped with coiled springs 1 or any other suitable means for sustaining a pad 60 or mattress C. When the couch is closed, as shown in Figure 3, the bottom section B of the mattress supporting means is arranged directly underneath the top section A and far enough below the same to enable the mattress 70 C to be maintained in a folded condition upon the bottom section B, the top section A then serving as a support for a removable upholstered seat D. To open the couch the upholstered seat is first removed from the top section 75 A of the mattress supporting means and said top section is thereafter pulled forwardly into the position shown in Figure 2, which operation causes the bottom section B to move upwardly into horizontal alignment with the 80 top section so as to enable the mattress C to be unfolded and spread out flat upon the two sections A and B. During the operation of pulling the top section forwardly into its extended position and during the operation of 85 pushing said top section rearwardly into its closed position, the bottom section B is caused to assume an angular position or downwardly-inclined position, wherein the front edge of said bottom section is spaced far enough away 90 from the rear edge of the top section A to eliminate the possibility of the rear edge of said top section striking against or rubbing upon the folded mattress C when the rear edge of the top section A is traveling over the front 95 edge of the bottom section B. This is one of the distinguishing characteristics of my improved couch and is a feature that adds greatly to its commercial utility, as it facilitates the opening and closing of the couch and makes it 100

practicable to store the bedding inside of the folded mattress, when the couch is closed, even if the mattress is comparatively thick.

In order that the sections A and B of the mattress supporting means and the operating mechanism combined with said sections may be installed easily in the couch, said parts are combined with two end plates or supporting members E that are connected in any suitable way to the end frames of the couch. The bottom section B is carried by two pairs of swinging members F and G pivotally mounted on the end plates E and pivotally connected to said bottom section B in such a way that said bottom section will assume an inclined position with its front edge tilted downwardly when said bottom section moves upwardly during the operation of opening the couch and when said bottom section moves downwardly during the operation of closing the couch. The members F and G can be constructed and arranged in various ways without departing from the spirit of my invention. In the embodiment 25 of my invention herein illustrated the members F consist of two bell crank levers on the end plates E whose long arms are pivotally connected at 2 to the end pieces of the bottom section B and whose short arms are attached to springs F' that constantly exert pressure on said bell crank levers F in a direction tending to swing the long arms of same upwardly. The swinging members G on the end plates E consist of links of less 30 length than the long arms of the levers F and provided with elongated slots 3 which receive pins 4 that project laterally from the end pieces of the bottom section B. When the couch is closed, as shown in Figure 3, the links G and the long arms of the bell crank levers F project downwardly, and thus hold the bottom section B of the mattress supporting means in a horizontal position at a point considerably below the top section A of said mattress supporting means. Said 35 top section A is also carried by two pairs of swinging members H and I pivotally mounted on the end plates E and pivotally connected to said top section. In the couch herein illustrated the members H consist of bell crank levers whose long arms are pivotally connected at 5 to the rear edge of the top section A and whose short arms are provided with lateral projections or grooved 40 rollers 6 that travel in elongated guides on the bottom section B of the mattress supporting means, which guides are herein illustrated as being formed by the end pieces of the bottom section and by bars or rails 7 45 arranged parallel to said end pieces and securely connected to same so as to form guideways at the ends of the bottom section B that co-operate with the lateral projectins or rollers 6 on the bell crank levers H to depress the bottom section B and to tilt the

front edge of said bottom section upwardly into horizontal alignment with the top section A during the operation of opening the couch. The swinging members I are herein illustrated as curved links pivotally connected at 8 to the top section A and each provided at one end with an angularly-disposed arm designated by the reference character 9 in Figure 5 that is pivotally connected at 10 to one of the end plates E. If desired, coiled springs I' can be connected to the angularly-disposed arms 9 of the links I in such a way that the tension of said springs is increased when the top section A is approaching the end of its forward movement, and when said top section is approaching the end of its rearward movement, thereby tending to prevent the sections of the mattress supporting means coming to rest with a sudden shock or jar during the operation of opening and closing the couch. The top section A is provided with pivotally mounted legs J for supporting the front edge of same when the couch is open, and in order that said legs will be extended and collapsed automatically 90 during the operation of opening and closing the couch, said legs are joined by links 11 to extensions 12 of the links I that project beyond the pivots 8 which join said links I to the top section A. 95

When the couch is closed the long arms of the bell crank levers H and the curved links I project rearwardly, as shown in Figure 3, thus holding the top section A of the mattress supporting means in vertical alignment 100 with the bottom section B. At such times the rollers or lateral projections 6 on the short arms of said levers H exert downward pressure on the bottom section B, and thus effectively hold said bottom section in its depressed position. When the top section A is moved forwardly during the operation of opening the couch the bell crank levers H and the links I swing upwardly and forwardly, thereby permitting the bottom section B to move upwardly under the influence of the springs F' that are connected to the short arms of the bell crank levers F that sustain the rear edge of the bottom section B. Due to the fact that said bell crank levers F are 115 longer than the link G which sustain the front edge of the bottom section B, said bottom section will assume an inclined position with its front edge tilted downwardly during the upward movement of said bottom section. At about the time the rear edge of the top section A is positioned above the front edge of the bottom section B, during the forward movement of said top section, said sections occupy substantially the position shown in 120 Figure 5, wherein it will be noted that the rear edge of the top section A is spaced far enough away from the front edge of the bottom section B to eliminate the possibility of said top section A striking against or rub- 125 130

bing upon the folded mattress C carried by the bottom section B. The continued forward movement of the top section A causes the rollers or lateral projections 6 on the short arms of the bell crank levers H to bear against the guide bars 7 on the bottom section B, and thus exert pressure on said bottom section in a direction to raise the front edge of said bottom section upwardly into horizontal alignment with the top section A by the time said top section reaches its extended or forward position. During the first portion of the upward movement of the bottom section B the bell crank levers F which sustain the rear edge of said bottom section come in contact with and are arrested by stops 13, on the end plates E. Thereafter, when the rollers 6 on the bell crank levers H exert upward pressure on the guide bars 7 connected to the bottom section to tilt the front edge of said section upwardly, said bottom section oscillates on the pivots 2 which join the same to the levers F. When the top section A is moved upwardly and rearwardly from its extended position to close the couch the front edge of the bottom section B swings downwardly while the rollers 6 on the bell crank levers H are traveling rearwardly in the elongated guides formed by the end pieces 30 of the bottom section B and by the guide bars 7 connected to said end pieces, thus permitting the rear edge of the top section A to clear the mattress C which has been doubled over or folded, as shown in Figure 5. During the 35 time the top section A is moving rearwardly over the bottom section B the rollers or lateral projections 6 on the bell crank levers H exert downward pressure on the bottom section while said rollers are traveling forwardly in said guideways, thus causing the links G and the bell crank levers F to swing downwardly and move the bottom section B from its inclined position shown in Figure 5 into its horizontal position shown in Figure 3. 40 While I prefer to sustain the rear edge of the bottom section B by bell crank levers F that are combined with springs F' which constantly exert pressure on the bottom section in a direction tending to move it upwardly, 45 it would be possible to use links to sustain the rear edge of the bottom section and operate the bell crank levers H in such a way that they would positively raise the bottom section B into an inclined position and there- 50 after tilt the front edge of said bottom section upwardly into the horizontal plane of the top section A during the operation of extending said top section. Accordingly, I 55 wish it to be understood that my broad idea 60 contemplates the use of an operating mechanism comprising elements actuated by the movement of the top section into its extended or closed positions and combined with the bottom section B in such a way that they 65 either permit or cause said bottom section

to move upwardly first into an inclined position and thereafter into a horizontal position parallel or substantially so with the top section when said top section is extended.

Having thus described my invention, what I claim as new and desire to secure by Letters Patent is:

1. A folding couch or davenport provided with a mattress supporting means that comprises two sections arranged horizontally, one above the other, when the couch is closed, the top section being adapted to be raised and moved forwardly, without reversing, into an extended position, and mechanism for moving the bottom section upwardly into the horizontal plane of the top section when said top section is extended, said mechanism being constructed so as to cause the bottom section to be held in an inclined position with its front edge tilted downwardly sufficiently to be cleared by the rear edge of the top section when said rear edge is traveling over the front edge of the bottom section.

2. A folding couch or davenport provided with a mattress supporting means that comprises two sections that have no direct connection with each other and which are arranged horizontally in superimposed relation when the couch is closed, the top section being adapted to be raised and moved forwardly into its extended position, or raised and moved rearwardly into its retracted position, without reversing or turning upside-down in either of said operations and the bottom section being adapted to move upwardly bodily into horizontal alignment with the top section during the operation of extending said top section and move downwardly bodily to a point below said top section when said top section is restored to its closed position, and means for causing the bottom section to assume an inclined position with its front edge tilted downwardly when said bottom section is being raised or lowered so as to insure the rear edge of the top section clearing the mattress that is maintained in a folded condition on said bottom section when the couch is closed.

3. A folding couch or davenport provided with a mattress supporting means that is composed of two sections arranged substantially horizontally, one above the other, when the couch is closed, the top section being adapted to move upwardly and forwardly, without reversing, into an extended position, and an operating mechanism combined with said sections and constructed in such a way that the forward movement of the top section into its extended position causes the bottom section to move upwardly into an inclined position with its front edge tilted downwardly out of the path of the rear edge of the top section and thereafter swing into a horizontal position parallel or substantially so with said top section.

4. A folding couch or davenport provided with a mattress supporting means that comprises two sections arranged substantially horizontally, one above the other, when the couch is closed, the top section being adapted to move upwardly and forwardly, without reversing, into an extended position, and an operating mechanism combined with said sections and constructed so that the bottom section will assume an angular position with its front edge tilted downwardly sufficiently to clear the rear edge of the top section when said top section is traveling over the front edge of said bottom section during the operation of opening or closing the couch. 70
5. A folding couch or davenport provided with a mattress supporting means that consists of a top section and a bottom section, the top section being adapted to move upwardly and forwardly, without reversing, into an extended position, and an operating mechanism combined with said sections for holding the bottom section in a depressed position underneath the top section when the couch is closed 75
- 10 and for causing said bottom section to move upwardly into an inclined position with its front edge tilted downwardly, during part of the forward movement of the top section, and thereafter swing into horizontal alignment 80
- 15 with said top section. 85
6. A folding couch or davenport provided with a mattress supporting means comprising a top section and a bottom section arranged substantially horizontally in superimposed relation when the couch is closed, the top section being adapted to be moved upwardly and forwardly over the front edge of the bottom section, without reversing, during the operation of opening the couch, and mechanism for 90
- 20 raising and lowering said bottom section, constructed to cause the same to assume an inclined position with its front edge tilted downwardly during certain portions of the raising and lowering operation so as to insure 95
- 25 the rear edge of the top section clearing the mattress or folded bedding that is carried by the bottom section. 100
7. A folding couch or davenport provided with a mattress supporting means composed 105
- 30 of a top section and a bottom section arranged in superimposed relation when the couch is closed, swinging members that carry the top section, and means connected directly to certain of said swinging members and arranged 110
- 35 to move transversely of said bottom section in guides on the end portions of same for raising and depressing said bottom section and causing the front edge of same to tilt downwardly during the operation of opening and closing 115
- 40 the couch. 120
8. A folding couch or davenport provided with a mattress supporting means composed of a top section and a bottom section that are arranged one above the other when the couch 125
- 45 is closed, the top section being adapted to move forwardly, without reversing, into an extended position, and swinging members that carry said bottom section pivotally connected to the front and rear portions of said bottom section and so proportioned as to cause the bottom section to assume an inclined position with its front edge tilted downwardly at certain points in the upward and downward movement of said bottom section, whereby the rear edge of the top section will clear the front edge of said bottom section when said top section is being extended and retracted. 130
9. A folding couch or davenport provided with a mattress supporting means composed of a top section and a bottom section arranged in such a way that the bottom section will move upwardly into horizontal alignment with the top section during the operation of opening the couch and will move downwardly to a point below said top section during the operation of closing the couch, the top section being adapted to be moved forwardly, without reversing, into an extended position, and pivotally mounted supporting members for said bottom section proportioned so that said section will assume an inclined position with its front edge tilted downwardly when said section is being raised and lowered, whereby the rear edge of the top section will clear the front edge of said bottom section 135
10. A folding couch or davenport provided with a mattress supporting means composed of two superimposed sections that are arranged in spaced relation when the couch is closed, a supporting structure, swinging bell crank levers on said supporting structure having their long arms pivotally connected to the top section of the mattress supporting means for moving said top section upwardly and forwardly, and devices on the short arms of said bell crank levers that travel transversely of the bottom section in elongated guideways in said bottom section for bodily moving said bottom section and causing the front edge of same to tilt downwardly when the top section is being extended and retracted. 140
11. A folding couch or davenport provided with a mattress supporting means composed of a top section and a bottom section arranged one above the other when the couch is closed, swinging bell crank levers having their long arms pivotally connected to said top section adjacent the rear edge of same, swinging links pivotally connected to said top section and co-operating with said bell crank levers to sustain said top section, a supporting structure swinging members on said supporting structure that carry the bottom section, and devices on the short arms of said bell crank levers arranged in elongated guideways in said bottom section. 145
12. A folding couch or davenport provided with a mattress supporting means composed 150

- of two sections arranged substantially horizontally in superimposed relation when the couch is closed, a mechanism for moving the top section upwardly and forwardly into an 5 extended position, a spring-actuated mechanism for raising said bottom section, constructed so that said section will assume an inclined position with its front edge tilted downwardly during the upward movement of 10 said section, and means operated by the movement of the top section into its open and closed positions for raising and lowering the front edge of said bottom section relatively to the means that sustains same.
- 15 13. A folding couch or davenport provided with a mattress supporting means composed of a top section and a bottom section arranged in superimposed relation with the front edge of said bottom section, spaced away from the 20 rear edge of said top section when the couch is closed, a spring-actuated means for sustaining said bottom section, constructed so as to move said section upwardly into an inclined position with its front edge tilted downwardly 25 during the operation of opening the couch, and a sustaining means for said top section operatively connected with the sustaining means of said bottom section in such a way that the front edge of said bottom section 30 will be raised upwardly into horizontal alignment with said top section during the operation of extending said top section.
14. A folding couch or davenport provided with a mattress supporting means composed 35 of a top section and a bottom section arranged in superimposed relation when the couch is closed, swinging links provided with elongated slots that receive lateral projections on the ends of said bottom section located adjacent 40 the front edge of same, swinging bell crank levers whose long arms are pivotally connected to said bottom section adjacent the rear edge of same, actuating springs for said bell crank levers connected to the short arms of 45 same, elongated guideways on said bottom section, and pivotally mounted supporting members for said top section, two of which are provided with angularly-disposed arms that are equipped with elements that travel in 50 the guideways on said bottom section.
15. A folding couch or davenport provided with a mattress supporting means composed of a top section and a bottom section arranged in superimposed relation when the couch is 55 closed, legs for sustaining the front edge of said top section when it is extended, a spring-actuated mechanism for raising the bottom section and holding it in an inclined position with its front edge tilted downwardly, and 60 means operated by the movement of said top section into and out of its extended position for opening and collapsing said supporting leg and for raising and lowering the front edge of said bottom section.
- 65 16. A folding couch or davenport provided with a mattress supporting means composed of a top section and a bottom section, stationary end plates, spring-actuated bell crank levers on said end plates pivotally connected to the rear edge portion of said bottom section, slotted links on said end plates pivotally connected to the front edge portion of said bottom section, elongated guideways arranged at the ends of said bottom section, 70 separate bell crank levers on said end plates pivotally connected to the rear edge portion of the top section and provided on their short arms with elements that travel in said guideways, and curved links on said end plates pivotally connected to said top section and combined with springs that tend to absorb the shock on said top section when it reaches its open and closed positions.
17. A folding couch or davenport provided with a mattress supporting means composed of a top section and a bottom section arranged in superimposed relation when the couch is closed, stationary end plates, slotted links on said end plates that sustain the front edge portion of said bottom section, spring-actuated bell crank levers on said end plates that sustain the rear edge portion of said bottom section, elongated guideways on said bottom section, bell crank levers for sustaining the rear edge portion of the top section pivotally mounted on said end plates and having their short arms equipped with elements that are arranged in said guideways, swinging links on said end plates pivotally connected to said top section and provided adjacent 85 their axis of movement with angularly-disposed arms, springs connected to said arms for the purpose described, and pivotally mounted legs on the top section for sustaining the front edge of same combined with said 90 swinging links in such a way that they will be opened and collapsed during the operation of opening and closing the couch.
18. A folding couch provided with a mattress supporting means composed of two superimposed horizontal sections that are arranged in spaced relation when the couch is closed, a supporting structure, swinging bell-crank levers on said supporting structure having their long arms pivotally connected to 100 the top section of the mattress supporting means for moving said top section upwardly and forwardly, means for bodily moving said bottom section upwardly and causing the front edge of the same to tilt downwardly 105 when the top section is being extended or retracted, said last named means including devices on the short arms of said bell crank levers and elongated transverse guideways in the bottom section in which said devices travel 110 during extension or retraction of said top section.
